UNITED STATES PATENT OFFICE

LOUIS LEBAU, OF PITTSBURGH, PENNSYLVANIA

ELECTRIC RADIANT HEATER

Application filed January 19, 1929. Serial No. 333,684.

This invention relates to an electric heater, and more particularly to a new and improved electric radiant heater.

In the embodiment thereof, as shown, I have illustrated a wall type of heater, but the present invention is not to be limited to this particular type, as it is evident that a different form of casing may be employed.

The prime object of the invention is to provide a new and improved heater embodying a refractory radiant member having a resistor element or elements of relatively thin flat current-conducting strips of suitable resistant material embodied in the refractory members, said refractory member or plate being of such a character that it may be readily positioned within and removed from the casing of the heater.

A further object of the present invention is to provide an electric supporting member of such a character that the resistor element of the form stated may be readily positioned in and removed from the supporting member; and new portions of the resistor replaced without the necessity of discarding the whole element.

In the accompanying drawings, which illustrate an application of my invention:

Fig. 1 is a front elevational view of a wall type of heater embodying my invention;

Fig. 2, an end elevational view;

Fig. 3, a vertical sectional view on the line III—III of Fig. 1;

Fig. 4, a vertical sectional view through the radiant, said section being indicated on the line IV—IV of Fig. 5; and

Fig. 5, a sectional view on the line V—V of Fig. 4.

Referring to the drawings, I have shown a wall type of an electric radiant heater constructed in accordance with my invention and, as illustrated, I have provided a casing made of suitable sheet metal comprising a rectangular or square hollow body portion, designated generally by the numeral 5, and comprising a back plate 6, top, bottom and side portions 7, the latter being secured to the back plate, the said sides, top and bottom each formed with openings 8 for the passage of air into the interior of the casing.

The interior of the casing is divided by a plate 9 to form front and back portions or chambers. This construction, including as it does plate 9 and the openings in the top, bottom and sides of the casing, provides for the circulation of cooling air, so that the structure may be positioned in or on a wall without danger of causing fire, due to excessive heat. The casing also includes a hollow front portion 10, of very similar construction as the hollow back portion. This front portion is also provided along its top, bottom and sides with openings 11 for the passage of air into and out of the casing 10.

This chamber or space 10 is designed to receive a plate, block or element 12 formed of refractory material and commonly termed a refractory plate or radiant. The refractory plate 12 constitutes a characteristic and important feature of the present invention, and, as shown, is disposed at the front of the chamber 10, partially closing the hollow front portion 10 of the casing and resting upon ledges 13 of the front portion of the casing.

As illustrated and as preferred, this resistor receiving and supporting element 12 comprises a hollow body formed of a suitable refractory material having a heat reflecting solid back portion 14 preferably provided with exterior vertically extending strengthening ribs 15 and an open work or grille front 16. The interior of the hollow body is divided by vertically extending partition walls 17 designed to form chambers for the reception of the resistor units, which are designed to be inserted from the top of the radiant or block 12. These partition walls, as well as the end walls of the hollow body, are formed with vertically extending grooves, slots, or recesses 18 to receive the edges only of the resistor units when the latter are placed within the hollow plate 12.

The preferred type of resistor element or elements employed by me comprises a plurality of electrically connected units consisting of relatively thin, flat sheet metal strips 19 having slots 20 cut therein, the slots being spaced apart and extending inwardly from opposite longitudinal edges of the

strips, the slots extending from one edge being arranged alternately to those along the opposite edge.

This arrangement of slots in connection with the strips forms as a whole a sinuous path for the passage of the electric current, and provides a highly efficient heating element or elements including a plurality of resistor units electrically connected. The respective units are connected to adjacent units at the top by connecting pieces, as shown at 21, and the electrical connection between the middle units is made at 22 by a bolt. It is evident that these units may be electrically connected otherwise than shown; it being the purpose to provide means whereby the units may be inserted and removed in pairs or separately.

The resistor units may be connected to the electric current wire 23 through suitable switch mechanism located in switch box 24 and the wires 25 and 26 extending therefrom.

I claim:

1. In an electric radiant heater comprising a casing, a hollow refractory radiant member supported in the casing and having a plurality of resistor-receiving chambers formed by vertically extending partition walls and an open-work front portion, said walls and front portion constituting integral portions of the radiant member, a series of electrically connected resistor units positioned in said chambers to the rear of said front portion, said units each including a relatively thin flexible current-conducting strip having transverse slots to provide a sinuous path for the current.

2. In an electric radiant heater comprising a casing, a hollow refractory radiant member supported in the casing and having a plurality of resistor-receiving chambers formed by vertically extending partition walls, a series of electrically connected resistor units positioned in said chambers, said units each including a relatively thin flexible current-conducting strip having transverse slots to provide a sinuous path for the current, said partition walls provided with vertically extending grooves to receive the longitudinal edges of the resistor units.

In testimony whereof I affix my signature.
LOUIS LEBAU.
